UNITED STATES PATENT OFFICE

99,905

DESIGN FOR A COMBINED HOSIERY DISPLAY AND PACKING FOLDER

John W. Sweeney, West Reading, Pa., assignor to
The Narrow Fabric Company, West Reading,
Pa., a corporation of Pennsylvania

Application March 31, 1936, Serial No. 61,879

Term of patent 14 years

To all whom it may concern:

Be it known that I, John W. Sweeney, a citizen of the United States of America, residing at West Reading, in the county of Berks and State of Pennsylvania, have invented a new, original, and ornamental Design for a Combined Hosiery Display and Packing Folder, of which the following is a specification, reference being had to the accompanying drawings, forming part thereof.

Fig. 1 is a perspective view of the folder in display or easel position, showing a hosiery form in place supported by the front flap of the folder, with an article of hosiery indicated by dotted lines in position on the form with the welt portion displayed;

Fig. 2 is a view of said folder in flat position with the front flap open and the hosiery form in place against the rear flap, including an article of hosiery on the form with welt displayed as indicated in dotted lines;

Fig. 3 is a view similar to Fig. 2 with the hosiery form omitted;

Fig. 4 is a face view of the folder in closed position, with marginal portions of the outer face of the front flap provided with simulations of a box or carton in perspective;

Fig. 5 is an inside view of the folder in flat completely extended position without the hosiery form;

Fig. 6 is a view of the exterior of the folder similar to Fig. 5; and

Fig. 7 is an enlarged edgewise view of the folder in closed position as shown in Fig. 4 with the hosiery form in place.

I claim:

The ornamental design for a combined hosiery display and packing folder as shown and described.

In testimony whereof I affix my signature.

JOHN W. SWEENEY.
